FLOAT CONTROL

Jacob Lee Turner, Milton, Mass.

Application June 4, 1938, Serial No. 211,827

1 Claim. (Cl. 175—320)

This invention relates to improvements in float controls. More particularly, it relates to improvements in the type of control disclosed by my co-pending application Serial Number 33,796 filed July 29, 1935, now Patent No. 2,120,048 granted June 7, 1938.

The present control embodies the features of a container having a lower chamber accessible to the liquid whose level is to be controlled and an upper chamber completely sealed off from the lower chamber. In the lower chamber is a float member comprising an armature member movable within a tube extending upward from the lower chamber into the upper chamber. Surrounding the upper end of the tube is a coil forming part of a circuit comprising means arranged to effect the opening or closing of a control valve or other electrical agency.

It is among the objects of the present invention to provide a simple, compact unit comprising the float and the coil and a simple circuit whereby the electrical reactions of the coil may be effectively utilized.

The best mode in which I have contemplated applying the principles of my present invention is shown in the accompanying drawing, but these are primarily illustrative for it is intended that the patent shall cover by suitable expression in the appended claim whatever features of patentable novelty exist in the invention disclosed.

In the drawing:

Figure 1 is a vertical medial section through my improved control, the float member being shown in elevation;

Figure 2 is a section taken as on line 2—2 of Figure 1; and

Figure 3 is a diagrammatic showing of the preferred electrical circuit to be employed with the control.

Referring particularly to Figures 1 and 2, the unit container comprises a bottom shell 1 with side outlets 2 and 3 and a bottom outlet 4. The upper side outlet 2 is connected by a pipe 5 to the receptacle holding a liquid above any high level which the liquid would normally reach. Either the other side outlet 3 or the bottom outlet 4 should be connected to the said receptacle below any low level which the liquid could normally reach. As here shown, the lower side outlet 3 is indicated as so connected by pipe 6 and the bottom outlet 4 is closed by a plug 7.

The upper end 1a of the bottom shell 1 is preferably cast somewhat thicker than the wall to provide an ample seat for an intermediate partition 8. This partition has a flange 8a nicely fit-

ting within the end 1a to which the partition is secured by the bolts 9. At the center of the partition is a threaded hub 8b having on its underside a rounded rim 8c. Within the lower end of this hub is screwed a disk or bushing 10 of stainless steel having a central hole or opening 10a.

Into the upper end of the hub 8b is screwed a tube 11 of low magnetic permeability which extends upward and has its upper end closed by a stud 12 of special design. This stud has a cylindrical portion 12a nicely fitting the bore of tube 11 and a flanged shoulder 12b engaging the upper edge of the tube. This upper edge and the shoulder are welded together as shown at 13. The upper end or threaded stem 12c of the stud extends through a hole 14a in the top of an upper shell 14 of the unit container. This shell has a reduced bottom edge 14b which fits nicely on a recessed edge 8d of the intermediate partition so that the external side surfaces of the bottom shell 1, the intermediate partition 8, and the upper shell 14 are in alignment. A nut 15 on the stud 12 secures the upper shell 14 firmly to the intermediate partition. A threaded hole 14c in the side of the upper shell is provided for the insertion of a suitable hollow plug through which extend waterproof cables 16 and 17.

These wires lead to a coil 18 which is wound about a tube 19 of insulating material; the latter tube fitting nicely around the hereinbefore described tube 11. Around the coil is an insulated shell 20 which is preferably formed by dipping the coil in a bath of molten insulating material, to form a coating thereof around the coil, after which the coil is removed from the bath and the insulated shell 20 permitted to harden. Around the insulated shell of the coil is a metal shell 21 of high magnetic permeability. This metallic shell is shown as having a cylindrical wall and end covers 21a and 21b each provided with a flanged edge to snugly fit around the ends of the cylindrical wall. These covers are provided with central holes whose edges fit nicely around the inner tube 11. Collars 22, with set screws 23 are provided at each end of the coil assembly to permit adjustment of the coil along the tube 11 and when suitably adjusted to hold it firmly in position.

After the position of the coil has been determined and the collars 22 secured to the tube 11, the shell 14 is tightly clamped to the intermediate partition 8 and then the upper or coil chamber in the shell 14 is completely filled with a waterproof material such as paraffin. This is admitted in a molten semi-liquid state through a

hole 10d near the top of the shell which is later closed by a plug. Thus when completely assembled, the coil and its electrical and magnetic adjuncts are completely waterproofed. Should it become necessary to readjust the position of the coil and to do anything else to the parts within the shell 10, the paraffin can be readily melted and poured out by holding the control upside down.

10 Within the lower shell 1 is a hollow ball or float 24 to which is connected a rod 25 extending upward through the hole 10a of the stainless steel guide disk 10. On the upper end of this rod is mounted an armature member 26, also of high magnetic permeability. When the level of liquid in the receptacle and in the bottom shell 1 is at some low level, such as $x-x$ for example, the float 24 is near the lower end of the shell, indeed may be resting on the rounded rim 1b of the bottom outlet 4. When the liquid rises to some predetermined upper level, as for example $y-y$, the float rises and effects movement of the armature 26 to a position within the coil 18, for example the position shown dotted in Figure 1. As will now be described this effects a material change in the characteristic of the circuit of which the coil is a part.

Referring now to Figure 3 the wires 27 and 27a of some suitable alternating current power line 30 (the first or primary circuit) are connected to the primary winding 28a of a transformer 28. A secondary circuit comprises the wire 16 leading from one end of the secondary winding 28b of this transformer to the coil 18. From the latter the wire 17 leads, as here shown, to a low capacity relay 29 and from the latter a wire 30 returns to the secondary winding 28b of the transformer.

Between the wires 16 and 17 is connected a condenser 31. The electrical characteristics of the coil 18 and condenser 31 are such that when the movable armature 26 is within the coil 18, for example in the position indicated in Figure 1 by the dotted outline, the secondary circuit is in a condition of resonance. When in this condition there is no effective flow of current in the secondary circuit, certainly not enough to energize the relay 29. Accordingly, the armature switch 32 will be drawn away from the coil of the relay by the spring 33. Thus a third circuit is open.

This third circuit comprises a wire 34 leading from wire 16 to a high capacity relay 35, this said relay, a wire 36 leading thence to the armature switch 32, this said switch, and a wire 37 connecting the latter to wire 30. Since this circuit is broken when switch 32 is open, the relay 35 is not energized and thus its armature switch 38 is drawn away from the relay by a spring 39. Thus a fourth circuit is open.

60 This fourth circuit comprises a wire 40 leading from the wire 27a of the main power line to the armature switch 38, this said switch, a wire 41 leading thence to a solenoid coil 42 and a connection 43 from the latter to the other wire 27 of the main power line. The solenoid 42 is here shown as controlling the position of a valve 44 in the supply line 45 for the liquid which is fed

to the container wherein the level of liquid is to be controlled. Instead of a valve, it is obvious that the solenoid might be utilized to actuate any other responsive agency.

Upon the liquid falling to some level such as $x-x$, Figure 1, thereby effecting the withdrawal of the armature 26 from the coil 18, the coil and condenser 31 will no longer be in resonance, thereby permitting an appreciable current flow through the secondary circuit sufficient to energize relay 29 and close the switch 32. This will establish flow through the third circuit and energize relay 35 to close switch 38. Closure of this switch closes the fourth or direct circuit from the power lines to the solenoid 42 and opens valve 44. This condition of the circuits is shown in Figure 3.

The valve 44 being thus open, the liquid in the container will rise until some level, such as $y-y$, is reached where the movable armature 26 is again within the coil 18.

The high magnetic permeability of the armature 26 together with the high magnetic permeability of the metallic shell 21 (21a and 21b) surrounding the coil, favors a flow of magnetic flux which appreciably affects the electrical characteristic of the coil by changing its impedance. When so affected, its electrical characteristic becomes such that, in conjunction with the condenser 31, the secondary circuit is in a condition of resonance, and thus the effective flow through the secondary circuit is reduced to the point where the relay 29 is not sufficiently energized to overcome the force of spring 33 and the switch 32 will thereupon be opened. Thence follow the closure of valve 44, as previously described, with consequent shutting off of the liquid flow through supply line 45 to the container. Thus the control restores the liquid level under control.

I claim:

Electric float control apparatus comprising a vertically disposed fixed tubular member of low magnetic permeability having its upper portion surrounded by a coil; a magnetic conductor of high magnetic permeability arranged externally of said coil; a transformer connected to a source of alternating electric current; a circuit connected to the secondary winding of said transformer and including said coil and a relay and a condenser arranged in the circuit in parallel with said coil; and a floating armature member of high magnetic permeability movable within said fixed tubular member into and out of the path of magnetic flux of said coil in accordance with changes in the level of a liquid; the said coil and said condenser having such relative electrical characteristics that upon the impedance of said coil being increased by the positioning of the movable armature within the path of magnetic flux of said coil the said circuit is placed in a condition of resonance with no effective flow of current sufficient to energize the relay, and that upon the impedance of said coil being reduced by the withdrawal of the movable armature from the path of magnetic flux of the coil effective current flow is established in said circuit sufficient to energize said relay.

JACOB LEE TURNER.
